UNITED STATES PATENT OFFICE

135,150

DESIGN FOR A PORTABLE SOUND AMPLIFICATION UNIT

Walker C. Cottrell, Jr., and Alexander S. Ganzert,
Jr., Richmond, Va., and Milton J. Shapp, Sil-
ver Spring, Md.

Application December 24, 1942, Serial No. 109,128

Term of patent 7 years

To all whom it may concern:

Be it known that we, Walker C. Cottrell, Jr., Alexander S. Ganzert, Jr., and Milton J. Shapp, citizens of the United States and residents of Richmond, Virginia, Richmond, Virginia, and Silver Spring, Maryland, respectively, have invented a new, original, and ornamental Design for a Portable Sound Amplification unit, of which the following is a specification, reference being had to the accompanying drawings, forming a part thereof.

In the drawings:

Figure 1 is a perspective view of a portable sound amplification unit showing our new design;

Figure 2 is an end elevational view thereof showing the end opposite to that visible in Figure 1;

Figure 3 is a side elevational view thereof showing the side opposite to that visible in Figure 1; and

Figure 4 is a top plan view thereof.

We claim:

The ornamental design for a portable sound amplification unit, as shown.

WALKER C. COTTRELL, JR.
ALEXANDER S. GANZERT, JR.
MILTON J. SHAPP.
